US00D984210S

(12) **United States Design Patent** (10) **Patent No.:** **US D984,210 S**
Tu (45) **Date of Patent:** **** Apr. 25, 2023**

(54) **BLENDER CONTAINER**

(71) Applicant: **SHARKNINJA OPERATING LLC**,
Needham, MA (US)

(72) Inventor: **Joyce Chien Tu**, Melrose, MA (US)

(73) Assignee: **SHARKNINJA OPERATING LLC**,
Needham, MA (US)

(**) Term: **15 Years**

(21) Appl. No.: **29/755,785**

(22) Filed: **Oct. 22, 2020**

(51) LOC (14) Cl. **07-04**

(52) U.S. Cl.

(57) **CLAIM**

The ornamental design for a blender container, as shown and described.

DESCRIPTION

FIG. 1 is a perspective view of a blender container showing our new design in an embodiment;

FIG. 2 is a front view of the embodiment shown in FIG. 1;
FIG. 3 is a rear view of the embodiment shown in FIG. 1;
FIG. 4 is a side view of the embodiment shown in FIG. 1;
FIG. 5 is another side view of the embodiment shown in FIG. 1;

FIG. 6 is a top view of the embodiment shown in FIG. 1;

and,

FIG. 7 is a bottom view of the embodiment shown in FIG. 1.

The broken lines in the drawings are for illustrative purposes only and form no part of the claimed design.

1 Claim, 7 Drawing Sheets
